FRANK W. GREEN AND NICHOLAS GREEN, OF OSHKOSH, WISCONSIN.

AUTOMOBILE-HEADLIGHT.

1,269,426.

Specification of Letters Patent. Patented June 11, 1918.

Application filed April 28, 1917. Serial No. 175,262.

To all whom it may concern:

Be it known that we, FRANK W. GREEN and NICHOLAS GREEN, citizens of the United States, residing at Oshkosh, in the county 5 of Winnebago and State of Wisconsin, have invented new and useful Improvements in Automobile-Headlights, of which the following is a specification.

This invention relates to headlights especially adapted to be used upon automobile machines and it consists in the novel features hereinafter described and claimed.

An object of the invention is to provide a headlight with means for swinging the 15 bulb support with relation to the reflector in order that the beams of light may be cast at a considerable distance in advance of the machine or may be cast in the path of travel of the machine in a downward direction and 20 comparatively close to the same.

With this object in view the headlight comprises a reflector of usual pattern in which a bulb supporting socket is pivotally mounted. The said socket is normally held 25 under the influence of a spring so that the rays of light from the bulb are cast in a downward direction in the path of travel of the machine and comparatively close to the same. However, when it is desired to cast 30 the rays of light in advance of the machine for a considerable distance an electromagnet is energized whereby the said bulb supporting socket is swung and the position of the bulb is changed with relation to the reflector and the rays of light are directed 35 approximately horizontal with relation to the surface of the roadway.

In the accompanying drawing:—

Figure 1 is a vertical sectional view of 40 the headlight showing the electric system in diagram;

Fig. 2 is a transverse sectional view of the same.

The headlight comprises a reflector 1 which is of the usual pattern and which is supported upon the frame of an automobile in a usual manner. A socket member 2 passes transversely through the center of the reflector 1 and is pivoted therein for 45 vertical swinging movement. The member 2 carries a bulb 3 of usual pattern and which is adapted to be connected with an electric circuit in a usual manner for illuminating 50

the same. A guide 4 is mounted at the back of the reflector 1 and a fork 5 is pivoted at the ends of its branches to that portion of the socket member 2 which is disposed behind the reflector 1. The shank of the fork 5 passes loosely through the guide 4 and is provided at its lower end with a head 6 which at times is adapted to have contact with the guide 4. A spring 7 is interposed between the guide 4 and the branches of the fork 5 and is under tension with a tendency to normally hold the fork 65 in an upper position and the forward end of the socket member 2 horizontally disposed within the reflector 1. A magnet 8 is mounted at the back of the reflector 1 and the core of the said magnet is located adjacent 70 the head 6 but normally from the same. Electric wires 9 are connected with the magnets 8 and also with a battery 10 and a terminal 11. A switch 12 is connected with one of the wires 9 and is adapted to be 75 moved into engagement with the terminal 11 whereby the circuit from the battery 10 to the magnet 8 along the wires 9 may be closed.

It is apparent that when the switch 12 is 80 at an open position the spring 7 will hold the socket member 2 so that the rays of light from the bulb 3 will be reflected by the reflector 1 in a forward direction in the path of travel of the machine. When however, 85 the switch 12 is closed into contact with the terminal 11 the magnet 8 is excited by the current which is generated in the battery 10 and the yoke 5 is drawn toward the core 90 of the said battery whereby the forward end of the socket member 2 is moved to an upper position within the reflector 1 and the rays of light from the bulb 3 are reflected by the reflector in a forward and downward direction in the path of travel of the machine. Thus it will be seen that a simple 95 and durable headlight is provided and that the same may be manipulated to cast the rays or beams of light comparatively close to the machine or at a distance from the 100 same.

Having described the invention what is claimed is:—

A headlight comprising a reflector, a socket member pivoted therein, a yoke pivotally connected with the socket member, a

guide mounted on the reflector and slidably receiving the shank of the yoke, a spring bearing on the guide and operating upon the yoke to hold the socket members at normal position, and electric means adapted to operate upon the shank of the yoke for moving the socket member to an abnormal posi-

tion, said means lying in the path of movement of the shank of the yoke and adapted to limit the movement of the same.

10

In testimony whereof we affix our signatures:

FRANK W. GREEN.
NICHOLAS GREEN.
